(57) **CLAIM**

We claim the ornamental design for toy rocket launcher, as shown and described.

DESCRIPTION

FIG. 1 is a front perspective view of a toy rocket launcher with launch tube;

FIG. 2 is a top plan view of the toy rocket launcher with launch tube of FIG. 1;

FIG. 3 is a bottom plan view of the toy rocket launcher with launch tube of FIG. 1;

FIG. 4 is a front plan view of the toy rocket launcher with launch tube of FIG. 1;

FIG. 5 is a right plan view of the toy rocket launcher with launch tube of FIG. 1;

FIG. 6 is a left plan view of the toy rocket launcher with launch tube of FIG. 1;

FIG. 7 is a rear plan view of the toy rocket launcher with launch tube of FIG. 1;

FIG. 8 is a front perspective view of the toy rocket launcher of FIG. 1 without the launch tube, showing an enlarged view for illustrative purposes;

FIG. 9 is a front plan view of the toy rocket launcher of FIG. 8;

FIG. 10 is a right plan view of the toy rocket launcher of FIG. 8;

FIG. 11 is a left plan view of the toy rocket launcher of FIG. 8;

FIG. 12 is a rear plan view of the toy rocket launcher of FIG. 8; and,

FIG. 13 is a bottom perspective view of the toy rocket launcher of FIG. 8.

The broken lines represent environmental structure and are shown for illustrative purposes only and form no part of the claimed design. The design shown is not to be limited to any particular size and may be scaled larger or smaller.
